UNITED STATES PATENT OFFICE.

FRANK A. PHILLIPPI, OF POTTSTOWN, PENNSYLVANIA, ASSIGNOR TO ADDISON R. MAY AND DANIEL L. EVANS, TRUSTEES, OF POTTSTOWN, PENNSYLVANIA.

COOLER.

1,286,764.

Specification of Letters Patent.

Patented Dec. 3, 1918.

Application filed November 24, 1915. Serial No. 63,241.

To all whom it may concern:

Be it known that I, FRANK A. PHILLIPPI, a citizen of the United States, residing in Pottstown, Montgomery county, State of Pennsylvania, have invented certain Improvements in Coolers, of which the following is a specification.

One object of my invention is to provide certain detail improvements in coolers of the relatively small type used for lowering the temperature of drinking water, beer and the like;—the construction being such as to cause the rapid cooling of the liquid passing through the device as well as a steady flow 15 thereof at the outlet of the device.

It is further desired to provide an efficient form of cooler with novel means for reducing to a minimum the foaming of the liquid operated on;—the arrangement of parts being such as to facilitate the inspection and 20 cleaning of the device as well as its inexpensive and economical construction.

These objects and other advantageous ends I secure as hereinafter set forth, reference being had to the accompanying drawings, in which,

Figure 1 is a central vertical section of a cooler constructed according to my invention;

30 Fig. 2 is a plan; and

Fig. 3 is a horizontal section taken through the pivots of the clamping bolts and through the outlet opening.

In the above drawings 1 represents an 35 elongated cylinder of relatively thin metal, which together with the other metal parts of the apparatus coming in contact with the liquid to be cooled is preferably made of German silver. To one end of the casing 1 is 40 sweated a base casting 2 while a collar 3 is likewise sweated to its opposite end. This collar has projecting from it, three or any suitable number of properly spaced lugs 4 to each of which is pivoted a clamping bolt 45 5 and these bolts are designed to extend between the branches of forked lugs 6 on a clamping plate 7 fitting over and holding against the upper end of the cylinder 1, there being wing nuts 10 operative on the 50 bolts and engaging this plate to retain it in its clamping position. Between the plate 7 and the top end of the casing 1 is confined a cover 9 which has an annular packing containing recess fitting over said end and making a liquid tight joint therewith when the

wing nuts are set up. The cover 9 has a central boss into which is screwed a threaded bushing 11 screwed or otherwise connected to a spherical shell 12 serving as an air chamber.

Within the casing or shell 1 is mounted a casting 13 preferably of porcelain constituting a baffle element having a central cylindrical portion 14 of such a diameter as to provide an elongated annular space or chamber between its surface and the inner walls of the shell or casing 1. At its lower end said casting has helical ribs 15 similar to the threads of a screw which extend to within a short distance of its lower extremity 60 and on the opposite end of the element 13 is a second helical rib 16 which with the rib 15, is of such dimensions as to closely fit the bore of the shell 1 and effectually prevent leakage of appreciable quantities of liquid 65 between the outer edge of any rib and the casing wall.

The base casting 2 is provided with a projecting boss 17 in which is threaded a bushing 18 whose inner end projects into the 70 channel formed between the lowermost portion of the rib 15 and the casing 1, it being noted that this bushing like a second bushing 21 threaded into a boss 20 of the collar 3, has the inner end of its passage curved so 75 as to discharge or receive liquid in a line practically at right angles to its center line. Moreover the walls of the passages of both of these bushings is formed in a gentle rather than in an abrupt curve so that fluid passing 80 therethrough has its direction of motion gradually changed. The bushing 21 in the boss 20 opens into the space defined by the upper end of the rib 16, the cover 9 and the wall of the casing 1, the top of the baffle element 13 having a projecting boss 22 engaged by said cover and transversely slotted or otherwise recessed at 23 to permit of the free flow of air between the casing and the interior of the air chamber 12.

Under conditions of use liquid entering the bushing 18 has its direction of flow changed thereby so that it passes into the tortuous channel provided by the rib 15 without being permitted to form eddies or 90 being so disturbed as to foam objectionably, it being understood that the cooler as a whole is placed within a suitable container and surrounded by ice or other cooling medium.

In passing through the channels provided by the rib 15 the liquid is forced to travel in intimate contact with a considerable portion of the inner surface of the casing 1 and thereafter enters the relatively large annular chamber or container formed between the central or unribbed portion 14 of the baffle element 13 and the wall of the casing. Obviously a considerable volume of liquid collects in this chamber and lies in contact with a further expanse of the inner surface of the casing, from which it passes into the tortuous channel formed by the rib 16 and thence into the bushing 21 where its direction of movement is changed so that it ultimately flows out of the casing 1 in a radial direction.

The space between the upper end of the main portion of the baffle element 13 and the cover 9 contains air or gas as does also the spherical chamber 12, with the result that any variations in the rate at which liquid flows to or is drawn from the cooler are minimized by the action of such gas which is compressed or permitted to expand by the changes of pressure of the flowing liquid due to the above noted variations in its flow.

When it is desired to inspect or clean the cooler, the cover and clamping plate may be quickly removed by taking off the wing nuts 10, whereupon the bushing 21 may be screwed outwardly until it is possible to lift out the baffle element 13.

I claim:

- 35 1. The combination in a cooler of a casing; a baffle element in the casing coöperating with the walls thereof to provide tortuous liquid circulating channels; with bushings threaded through the casing walls and 40 communicating with said channels to provide an inlet and an outlet for the casing; the passages of said bushings opening into the casing in lines substantially at right an-

gles to the bushing center lines and within the cylindrical surface outlining the bushing. 45

2. The combination in a cooler of a casing; a baffle element therein formed to co-operate with the inner surface of said casing to provide a tortuous liquid circulating channel; a cover for the casing; with a device for rendering the liquid flow uniform consisting of a closed air chamber mounted on the cover and communicating with the upper part of the tortuous channel of the casing. 55

3. The combination in a cooler of a substantially cylindrical casing; means for causing liquid to circulate therein; a cover removably closing one end of the casing; with means for rendering the liquid flow 60 uniform consisting of an air chamber carried by the cover and communicating with the interior of the casing.

4. The combination in a cooler of a substantially cylindrical casing; a baffle element 65 mounted therein and having a centrally projecting portion formed with a side opening recess in its top face; a cover removably closing one end of the casing; with an air chamber on the cover communicating with 70 the interior of the casing through the recess in the projecting portion of the baffle element.

5. The combination in a cooler of a casing; and a baffle element consisting of an integral body of porcelain having two channeled portions respectively adjacent its ends and fitting against the walls of said casing to form passages and a part of reduced diameter connecting said portions to form with 75 the casing an annular reservoir, said casing having an inlet and an outlet respectively communicating with the passages formed by said channeled portions of the baffle element. 80

FRANK A. PHILLIPPI.
